Allen Greely
Letters Patent

2408X

The Schedule referred to in these Letters Patent and making part of the same containing a description in the words of the said Allen Greely himself of his improvement in the fast Stove.

The Stove consists principally of the following parts. A bail or handle, an outside case of wood, an inside case or lining of sheet iron, and heater being either a block of fire stone, a tile or two brick bats, & a door on one side lined with sheet iron -

The Stove to be made generally, not far from nine inches square, and three inches and a half high, the outside case and the inside lining to be fastened together, the heater after being heated to be placed within the lining, the door either to shut or to open and shut with hinges, the handle or bail to extend from one side to the other of the stove.
